UNITED STATES PATENT OFFICE.

ALFRED ROESCH, OF BROOKLYN, NEW YORK, ASSIGNOR OF TWO-THIRDS
TO WILLIAM B. WADSWORTH, OF PLAINFIELD, AND FREDERICK H.
DAVIS, OF ELIZABETH, NEW JERSEY.

THERMOSTAT.

SPECIFICATION forming part of Letters Patent No. 583,633, dated June 1, 1897.

Application filed October 24, 1896. Serial No. 609,935. (No model.)

To all whom it may concern:

Be it known that I, ALFRED ROESCH, a citizen of the United States, residing at Brooklyn, in the county of Kings and State of New York, have invented new and useful Improvements in Thermostats, of which the following is a specification.

My invention relates to improvements in thermostats for regulating the temperature of buildings.

The objects of my invention are, first, to multiply or increase the power of a thermostat; second, to increase the range or length of movement of a thermostat, and, third, to provide improved means of adjusting the thermostat for various temperatures.

It is obvious that by combining two or more compound bars or thermostatic bends of a given strength and range of movement in a single series the power of the thermostat will be doubled or multiplied by two or more, in proportion to the number of compound bars used in a series, while the length of movement would be no greater than that of a single compound bar. It is also obvious that by combining two or more series of such bars together the range or length of movement will be doubled or multiplied by two or more, in proportion to the number of series of compound bars thus combined together. By my improvement I combine several compound bars in a single series to increase the power of movement, and I also combine several series of such compound bars together to increase the range or length of movement.

The construction of my invention is further explained by reference to the accompanying drawings, in which—

Figure 1 represents a front view. Fig. 2 is a side view. Fig. 3 is a cross-section drawn on line $\alpha\alpha$ of Fig. 2, and Figs. 4 and 5 are details.

Like parts are referred to by the same reference-letters throughout the several views.

The thermostat proper consists of a double series of compound bars A and a double series of compound bars B, which series A and B are composed of two sets of compound bars C and D, which are preferably formed in the U shape shown. Each of the compound bars

C and D is formed in the usual manner by uniting two plates *a* and *b* of metal or other equivalent material of different expansibility.

The double series of compound bars A is supported from the long arm of the pivotal lever E, to which they are secured by the bolts F, the lever E being made of sufficient width to support the series of compound bars A. A top view of the lever E is shown in Fig. 4.

The double series of compound bars B is supported from the free ends of the series of bars A, to which they are secured by the bolts I and cross-bar J. The free ends of the double series of the compound bars B are connected with the vibrating arm K by bolts L, the connected end of the arm K being broadened or made of sufficient width, as indicated in Fig. 5, to engage the free ends of all the compound bars in the upper series B.

N are separating-blocks which are interposed between the ends of the single compound bars C and D.

The supporting-lever E is pivoted to the standards O O of the thermostat-frame upon trunnions P P, and said lever and the compound bars A, supported thereon, are adjusted to conform to the various temperatures desired by the bearing-screw Q and supporting-spring R. The screw Q is provided with an indicating-arm S, by which it is turned downward or upward in its supporting screw-threaded bearing T. When said screw Q is turned downward against the short arm of the lever E, the compound bars are thrown upward by the long arm of said lever, whereby the desired action of the thermostat is accelerated, while by turning said lever in the opposite direction the opposite result is attained. An indicating-dial A', provided with characters or marks, is located beneath said indicating-arm S, by which the adjustment of said arm is regulated.

The free end of the arm K is adapted to actuate the air-controlling valves of a heat-regulating system, and said valves are moved more or less promptly with greater or less power, according to the flexibility or rigidity of the compound bars to which it is attached. By diminishing the flexibility of the com-

pound bars they act more promptly and with greater power. The compound bars are made more or less rigid, as desired, by the action of the spiral spring C', adjustable screw D', and hand-nut E', by which the lever F is connected with the valve-actuating rod K. It is obvious that by drawing up the screw D' the tension of the spring C' is increased, which has the effect to compress the U-shaped bends 10 of the compound bars and make them more rigid, in which condition they act, as stated, more promptly and with increased power, whereby the thermostat is more sensitive in its action to slight changes of temperature, 15 while by the reverse movement of said screw D' the tension of said spring C' is diminished, and the opposite result is attained.

While I have shown and described a combination of several series of compound bars 20 secured in sets to each other for increasing the length or range of movement of the valve-actuating arm, it is obvious that when the required length of movement will permit a less number of series or a single series of 25 compound bars may be used instead.

Having thus described my invention, what I claim as new, and desire to secure by Letters Patent, is—

1. In a thermostat for regulating temperature, the combination of two or more compound or thermostatic bars in a single series; 30 two or more series of compound bars secured in sets to each other; a lever for supporting the several series of compound bars; a valve-actuating arm connected with the free ends 35 of the second or outer series of said compound bars; and means for adjusting the supporting-lever of said compound bars, substantially as and for the purpose specified.

2. In a thermostat for regulating tempera- 40

ture, the combination of two or more compound or thermostatic bars in a single series; a lever for holding and adjusting said series of compound bars; a screw for adjusting said lever in one direction; a counteracting-spring 45 for supporting said lever against the bearing end of said screw; an indicating-arm for turning and adjusting said screw against said lever; and a dial located beneath said arm to indicate the proper adjustment of said screw, substantially as and for the purpose specified.

3. In a thermostat for regulating temperature, the combination of two or more compound or thermostatic bars in a single series; 50 two or more series of compound bars secured in sets to each other; a lever for holding and adjusting said series of compound bars; a screw for adjusting said lever in one direction; a counteracting-spring for supporting 55 said lever against the bearing end of said screw; an indicating-arm for turning and adjusting said screw against said lever; a dial located beneath said arm to indicate the proper adjustment of said screw; a valve- 60 actuating arm secured to the free end of the second or outer series of compound bars; a spring communicating between said actuating-arm and the supporting-lever of said compound bars; and means for regulating the 65 tension of said counteracting-spring between said actuating-arm and supporting-lever, all substantially as and for the purpose specified.

In testimony whereof I affix my signature in the presence of two witnesses.

ALFRED ROESCH.
